UNITED STATES PATENT OFFICE.

RUFUS H. MAURER, OF BROOKLINE, MASSACHUSETTS, ASSIGNOR TO SPENCER THERMOSTAT COMPANY, OF CAMBRIDGE, MASSACHUSETTS, A CORPORATION OF MASSACHUSETTS.

PILOT CUT-OFF FOR GAS BURNERS.

Application filed September 16, 1927. Serial No. 219,940.

This invention relates to gas burners and more particularly to heating gas burners, which in some cases are provided with pilots for relighting them when necessary, and having automatic means for cutting off the flow of gas in the event that the pilot and the main burner are extinguished.

Heating by gas is now very common for water heaters, stoves and certain types of automatic refrigerators and it is customary to vary and in some cases to cut off the heat applied by automatic or manually controlled devices, the burners being often relatively inaccessible. For the purpose of insuring the continuous automatic action of burners of this character, it is customary to provide a pilot to relight the main burner when necessary, although the pilot need not be used if the controlling means is adapted merely to regulate the height of the flame of the main burner. It sometimes happens in this latter case that the flame in the main burner is accidentally extinguished, or in the case where a pilot is used and the main burner is intentionally extinguished, the pilot also goes out; so that when the flow of gas to the main burner is reestablished, it is not ignited, but escapes to the surrounding parts of the building in which the burner is located with the attendant risks to the occupants both from fire and asphyxiation.

Among the objects of the invention, therefore, are to provide an automatic shut-off responsive to the burner and to the pilot if one is used, which will function quickly and in a certain manner to cut off the flow of gas to the main burner in the event that the flame in both the main burner and pilot, if one is used, is extinguished; to provide in a device of this character a cut-off valve so located as to be out of the heat range of the burner and consequently more durable and less likely to get out of order; to provide means associated with the pilot or the burner for insuring a positive action of the cut-off means; and generally to improve devices of this character.

Other objects and advantages of the invention will be apparent from the following specification and appended claims when taken in conjunction with the accompanying drawings, in which:

Fig. 1 is an elevation of a burner and thermostat associated therewith; and

Fig. 2 is a central section through the valve, 55 thermostat and pilot.

I have shown the invention associated with a burner of the Hoffman type, comprising a gas and air mixture 1, a mixing chamber 2, and a burner cap 3, gas being introduced through a pipe 4 in which is interposed an automatically controlled valve generally indicated at 5. A pilot nozzle 6 is provided adjacent to the burner cap 3 to relight it when necessary, this nozzle being supplied with gas through an elongate tube 7 which is threaded into a boss 8 preferably formed integral with the casing of the valve 5, a jam nut 9 being provided, if desired, to hold the tube 7 securely in the boss. A drill hole 10 extends from the interior of the valve casing 5 from the inlet chamber 11 thereof to the interior of the tube 7.

The valve 5 is similar to the ordinary globe valve having a wall 12 separating the inlet chamber 11 from the outlet chamber 13, an enlarged aperture 14 being formed in the wall 12 and having at one side a beveled valve seat 15 adapted to receive the beveled edge of the valve 16 which is forced upwardly on its seat by some suitable resilient means, such as the helical spring 17. The valve 5 may be provided with an enlarged plug 18 threaded into the valve casing at 19 to permit access to the interior thereof.

The valve casing is provided with a boss 20 opposite the boss 8 and in which is located the bore 10, a central bore 21 being provided in both bosses in which is journalled for longitudinal motion an elongate rod 22 having its lower end 23 received in a central recess in the valve 16. The upper end of the rod 22 is reduced and threaded as shown at 24 and extends through thermostatic disk 25, being fixed thereto by a nut 26 or in any other suitable manner. The disk 25 is provided with one or more perforations 27 to permit the passage of gas from the interior of the tube 7 to the pilot nozzle 6.

The pilot nozzle 6 is provided with an enlargement 28 which may be integral therewith and which is provided with an overhanging flange 29 adapted to engage the outer periphery of a substantially similar enlargement 30 which may be integral with the tube 7, the thermostatic disk 25 being mounted between the members 28 and 30. In order that the disk 25 will not be so tightly grasped

by the members 28 and 30 as to prevent its efficient operation, a spacer ring 31, which should be slightly (e. g. .005 inches) thicker than the disk is preferably provided between 5 said members, the inner diameter of the ring 31 being slightly greater than the diameter of the disk 25 as indicated in the drawings to prevent binding. The details of the mounting of the thermostatic disk do not, however, 10 form any part of the present invention.

The disk 25 is preferably bi-metallic, being formed of two component disks welded together, the materials such as iron and brass of the respective disks having different coefficients of expansion. The disk 25 is normally cupped (as by swaging) in such direction that the component part having the higher coefficient of expansion is on the concave side. Consequently upon raising the 15 temperature of the disk the unequal expansion of the materials forming the disk will cause a tendency to flatten the cupped surface until at a predetermined temperature a sudden curving in the opposite direction occurs, 20 which reversal of shape will be maintained until the temperature has been substantially lowered. Thereafter, upon reaching a substantially lower temperature, the disk will suddenly return to its initial shape. The 25 materials and thickness of the component parts and the degree of curvature are so chosen that the disk will snap in one direction when heated to the desired temperature (e. g. 120° F.) and will snap back at a lower temperature 30 (e. g. 100° F.). Suitable materials are sheet brass and nickel steel having a thickness of .005 and .005 inches respectively and suitable cupping for a disk $\frac{3}{4}$ inches in diameter is .02 inches.

40 It will be understood, however, that the present invention is not limited to any particular combination of materials having different thermal coefficients of expansion but is intended to embrace in its scope any combination of materials having dissimilar thermal coefficients of expansion sufficient to cause the reversal of curvature. Furthermore, the two materials comprising the composite thermostatic disk may be secured together in any desired manner by riveting, 45 soldering, brazing, or otherwise although it is preferred to unite the materials comprising the disk by welding or similar means to secure a substantially indivisible sheet.

55 I provide an auxiliary means in addition to the pilot and the main burner for keeping the thermostatic disk heated during the operation of the pilot, such means in the present instance being one or more perforations 60 32 here shown as located in the pilot tube 6 above the thermostat and through which gas may flow to feed small flame jets closely adjacent to the member 28 which in turn imparts the heat to the thermostat both by conduction 65 and radiation. It is contemplated that these

jets may, if desired, be located below the thermostatic disk rather than above it.

From the above description, the operation of the device should be obvious. During the operation of either the burner, the pilot, or 70 the small jets, the thermostatic disk will be heated, and flexed in a position opposite to that shown in Fig. 2 so that the rod 22 will be in its lowermost position, thus keeping the valve 16 off of its seat against the tension 75 of the spring 17. If, however, the flames are extinguished for any reason, the thermostatic disk will cool below its critical point and snap abruptly into the position shown in Fig. 2, thus drawing the rod 22 upwardly and permitting the spring 17 to close the valve 16 and thus cut off the gas feed to the main burner. While the gas fed to the pilot is uninterrupted, the leakage from this source will be so slight as not to cause any appreciable danger.

Inasmuch as many modifications of my invention will appear to those skilled in the art, I do not wish to be limited except by the scope of the appended claims.

I claim:

1. The combination with a gas burner and a gas supply pipe therefor of a valve in the pipe at a point remote from the burner so as not to be appreciably heated thereby, resilient means tending to keep said valve closed, a long rod loosely engaging said valve, a bimetallic snap acting thermostat mounted at the free end of said rod, said long rod being enclosed by a pipe leading from said valve, flanges enclosing said thermostat, a pilot nozzle mounted on one of said flanges adjacent said main burner to relight it when necessary and means for allowing a supply of gas from said valve to go through said long pipe, through said thermostat and to said pilot burner.

2. The combination of a thermostatically controlled pilot burner and valve, said valve comprising two chambers connected by an opening, a valve member adapted to close or open said opening when necessary, resilient means tending to keep said valve member in a closed position, a rod engaging said valve member and having a thermostat mounted at its free end, a pipe connected to said valve and surrounding said rod, flanges surrounding said thermostat, a pilot nozzle mounted on one of said flanges, a main burner adapted to screw on one side of said valve and directly communicating with one of said chambers, a gas supply pipe adapted to screw on the other side of said valve and directly communicating with the other chamber, said valve adapted to be connected so either one of said chambers is in communication with said supply pipe whereby the pilot nozzle may obtain its supply of gas from either the supply or main burner side of the valve.

3. The combination with a gas burner and

a gas supply pipe therefor of a valve in the pipe at a point remote from the burner so as not to receive an appreciable amount of heat therefrom, resilient means tending to 5 keep said valve closed, a long rod engaging said valve, a snap acting thermostat mounted at the free end of said rod and having apertures therein, a pipe connected to said valve and surrounding said rod, flanges surround-

ing said thermostat, a pilot nozzle supported 10 by one of said flanges in proximity to said main burner to relight it whereby said pilot nozzle obtains its supply of gas from the main valve through the long pipe and thermostat.

Signed by me at Cambridge, Mass., this 14th day of September, 1927.

RUFUS H. MAURER.
